CIRCUIT BREAKER

Donald E. Wise, South Bend, Ind.

Application August 4, 1945, Serial No. 608,935

3 Claims. (Cl. 200—88)

1

My invention relates to circuit breakers and has particular reference to such devices which automatically break the circuit upon the occurrence of an overload.

Important objects of the invention are to provide a circuit breaker which is small, simplified and has a low cost of production; to provide a circuit breaker having the size and appearance of the standard wall switch; to provide a circuit breaker so designed that it will fit into a standard commercial wall switch box and face plate; to provide a circuit breaker which is interchangeable with a standard commercial wall switch and can be substituted therefor; to provide a circuit breaker of such simplified construction that only one pin, rivet or screw is used in the complete assemblage for holding the main parts together; to provide a circuit breaker wherein the automatic circuit breaking device is trip free from the handle; to provide a circuit breaker wherein the automatic circuit breaking device is released by the action of a thermostatic element under light overloading conditions, and on heavier overload conditions or short circuits by an electromagnet; to provide a circuit breaker in which, under normal operating conditions with no overload or short circuit, the circuit breaker is operated as a manually operated switch; and to provide a circuit breaker wherein the contact or breaking operation is quick, upon either manual or automatic operation.

Other objects and advantages of the invention will be apparent during the course of the following description.

In the accompanying drawings forming a part of this application and in which like numerals are used to designate like parts throughout the same.

Figure 1 is a perspective view of a circuit breaker or switch embodying my invention.

Figure 2 is a transverse section taken on line 2—2 of Figure 5.

Figure 3 is a central longitudinal section taken on line 3—3 of Figure 2, with the operating handle in the "Off" position.

Figure 4 is a similar view with the operating handle in the "On" position.

Figure 5 is a similar view of the operating handle in the neutral position and the circuit opened.

Figure 6 is a horizontal section taken on line 6—6 of Figure 3, and

Figure 7 is a perspective view of the trip lever and associated elements.

2

In the drawings, wherein for the purpose of illustration is shown a preferred embodiment of my invention, the numeral 10 designates a casing as a whole, which is formed of suitable insulating material, such as "Bakelite." This casing includes ends 11, a top 12 and bottom 13. The top is provided with an elongated opening 14, having parallel side walls 15 and circularly curved end walls 16. The circularly curved end walls 16 are concentric with each other and with pivots 17, to be further described. The casing 10 further comprises sides 18 and 18'. The casing 10 is vertically split at 19', forming a major casing section 20', and a minor casing section or cover 21', held together by a single pivot element or pin 19, the ends of which may be spread, or this pin may have screw threaded engagement with the sides 18 and 18', or attached thereto by any suitable means. The side 18 has projections or places 18a to enter the major casing section 20'.

The major casing section 20' is provided upon the inner face of one end 11 with a recess 20, for receiving a stationary contact 21, having a contact part or point 22. The stationary contact is held in place by a binding screw 23, having screw threaded engagement therewith, and this binding screw extends to the exterior of the casing for connection with a wire 24. The opposite end 11 of the major casing section 20' has a recess 25, for receiving the lower end of a bi-metal thermostatic element 26. This lower end has a screw threaded opening 27 for receiving a binding screw 28, extending to the exterior of the casing for engagement with a wire 29. The bi-metal thermostatic element has an intermediate curved portion 30 and is provided at its upper end with a latch-head 31, as shown. The same end 11 of the major casing section 20' has a recess 32 near and above the recess 25, for receiving an electromagnet 33, including a core 34 and winding 35. This electromagnet may be held in place by any suitable means and may have a part thereof molded into the end 11. One end of the winding is electrically connected with the latch-head 31 by a wire 36, having suitable slack.

The numeral 37 designates a movable or swinging contact, the upper end of which is equipped with an apertured knuckle 38, pivotally mounted upon the pin 19. This apertured knuckle has an upstanding crank 39, formed integral therewith, and this crank is provided at its upper end with a ball 40. The crank 39 is slightly inclined with respect to the movable contact. The movable contact 37 is provided near its lower end with a

contact part or point 41, arranged to engage and disengage the stationary contact part 22, as shown. A wire 42, having sufficient slack, is electrically connected with the movable contact 31 and with one end of the winding 38.

The numeral 43 designates a trip-lever, including a bottom 44 and sides 45. The sides 45 are provided with upwardly projecting dogs or extensions 46. The sides 45 are provided at their ends with spaced apertured knuckles 47, arranged upon the opposite sides of the knuckle 38, and pivoted upon the pin 19. The trip-lever 43 tapers toward its end remote from the pin 19 and its bottom is inclined or rounded adjacent to its tapered end, as shown at 47, for coaction with the upper inclined face 48 of the latch-head 31. The bottom 44 of the trip-lever is provided with a boss or stud 49, extending into the upper end of a compressible coil spring 50, the lower end of which receives a boss or stud 51, carried by a stationary lug 52, formed integral with the bottom 13 of the major casing section 20'. It might be stated at this point that the free end of the trip-lever 43 may engage beneath and be held by the latch-head 31, in opposition to the spring 50. When the thermostatic element 26 is heated, due to an overload, its upper end moves laterally from the free end of the trip-lever 43, whereby the trip lever is released by the latch-head 31 and the spring 50 will then swing the trip-lever upwardly.

The numeral 53 designates an operating lever, having a base 54. This operating lever is mounted within the opening 14 and has flat parallel sides 55 to slidably engage the sides 15 and circularly curved end sides 56, to slidably engage the end walls 16. The base 54 carries the pivots 17, preferably formed integral therewith. The circularly curved ends 56 are concentric with the pivots 17 and with the end walls 16, as shown. The top 12 of the casing sections 20' and 21' is provided with openings 57, for pivotally receiving the pivots 17. The base 54 has a shoulder 54' to engage the trip-lever 43 and reset it. The base 54 has a recess 58 receiving a compressible coil spring 59, the upper end of which receives a ball 60, formed integral with the operating lever, as shown. The lower end of the spring 59 receives the ball 40. The spring 59 is stiffer or stronger than the spring 50 and can overcome the action of the spring 50.

The operation of the switch is as follows:

In the absence of a light overload or heavy overload or short circuit, the circuit breaker is used as an ordinary wall switch. When the operating lever 53 is swung to the right sufficiently so that the ball 60 moves beyond the dead center of ball 40, the spring 59 quickly swings the movable contact 31 to the "on" position, contact parts 22 and 41 engaging, Figure 4. When the operating switch 53 is swung to the left until the ball 60 passes the dead center of the ball 40 when the movable contact is in the "on" position, then the spring 59 quickly swings the contact 31 to the "off" position, Figure 3. During these operations, the trip-lever 43 is held in the retracted position by engaging behind the latch-head 31. When the swinging contact 31 is in the "on" position, Figure 4, and a light overload occurs, the increased current passing through the bi-metal thermostatic element 26 heats this element and the thermostatic element moves the latch-head 31 out of engagement with the trip-lever 43, and spring 59 swings the trip-lever toward the crank 38. The dogs 46 now engage crank 38 and overcoming the action of the spring 59, since spring

50 is stronger than spring 59, swing the contact 31 to the "off" position. The operating lever 53 now assumes an intermediate position, Figure 5. To reset the trip-lever 43, the operating lever 53 is swung to the left to the extreme "off" position, and the shoulder 54' will depress the trip lever and restore it to its position beneath the latch-head, the thermostatic element having now cooled and returned to its normal position. This restoring of the trip-lever in no way moves the swinging contact 31. When the contact 31 is in the "on" position, Figure 4, and a high overload or short circuit occurs, the electromagnet 34 is quickly energized before the thermostatic element 26 has had time to sufficiently heat for functioning, and this electromagnet draws the free end of the thermostatic element from the trip-lever 43, whereby the latch head 31 releases the trip-lever. This trip-lever then operates to swing the contact 31 to the "off" position. The trip-lever is reset in the manner stated. The bi-metal thermostatic element 26 is formed of two metals one of which would be iron so that it is attracted by the electromagnet. The element 26 is sufficiently resilient to return to its normal position when released by the magnet.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. A circuit breaker, comprising a support, an operating lever pivotally mounted upon the support, a main pivot mounted upon the support and separate from and in substantial alignment with the pivot of the operating lever, a swinging lever pivotally mounted between its ends upon the main pivot and including a crank disposed upon the same side of the main pivot with the operating lever, the crank being shifted to positions upon opposite sides of the pivot of the operating lever when the swinging lever is moved upon its pivot, a compression spring extending substantially axially of the operating lever and having one end secured to the operating lever and its opposite end secured to the end of the crank, a trip lever mounted upon the main pivot and having a part to contact with the crank when the trip lever is swung toward the crank and operating lever, a compression spring engaging the trip lever and arranged upon that side thereof remote from the first named compression spring, circuit closing means operated by the swinging lever, and releasable latch means to engage the trip lever, the arrangement being such that the trip lever when released is shifted toward the operating lever and crank to move the crank.

2. A circuit breaker, comprising a support, an operating lever pivotally mounted upon the support and including a base provided with a recess extending axially of the operating lever, a main pivot separate from the pivot of the operating lever and mounted upon the support, a swinging lever pivotally mounted between its ends upon the main pivot and including a crank disposed upon the same side of the main pivot with the base, the crank being shiftable to positions upon opposite sides of the pivot of the operating lever, a compression coil spring extending axially within the recess and having one end secured to the operating lever and its opposite end secured to

the end of the crank, a trip lever mounted upon the main pivot and having a lateral extension projecting toward the operating lever and crank to engage the crank and move it, a compression coil spring engaging the trip lever and arranged upon that side of the trip lever remote from the lateral extension, a releasable latch device to engage the trip lever, and circuit closing means operated by the swinging lever.

3. A circuit breaker, comprising a support, an operating lever pivotally mounted upon the support and including a base provided with a recess extending axially of the operating lever, the operating lever being provided with an internal head at the closed end of the recess, a main pivot mounted upon the support and spaced from the pivot of the operating lever and in substantial alignment therewith, a swinging lever pivotally mounted between its ends upon the main pivot and including an arm and a crank, the crank being angularly disposed with respect to the arm and arranged upon that side of the main pivot next to the base and having a head at the free end of the crank, a compression coil spring extending axially within the recess and receiving the heads in its opposite ends, a trip lever mounted upon the main pivot and having a lateral extension projecting toward the operating lever and crank to engage the crank when the trip

lever is swung toward the operating lever and crank, a compression coil spring engaging the trip lever and arranged upon that side thereof remote from the crank and first named compression coil spring, a releasable latch device for co-action with the trip lever, and means to limit the movement of the swinging lever in opposite directions including a circuit closing device.
